ABRASIVE HAND TOOL

Robert W. Martin, 1057 Pennington Road,
Trenton, N.J. 08618

Filed Apr. 4, 1969, Ser. No. 16,577

Term of patent 14 years

Int. Cl. D8—02

U.S. Cl. D8—91

FIG. 1.

FIG. 2.

FIG. 3.

FIGURE 1 is a perspective illustrating an abrasive hand tool embodying my new design;

FIGURE 2 is a side elevation of the abrasive hand tool illustrated in FIGURE 1; and

FIGURE 3 is an end view of the abrasive hand tool illustrated in FIGURE 1.

I claim:

The novel design for an abrasive hand tool, as illustrated in the drawing.
